UNITED STATES PATENT OFFICE

2,576,717

SUCTION CLEANER FILTER

Dale C. Gerber, North Canton, Ohio, assignor to
 The Hoover Company, North Canton, Ohio, a
 corporation of Ohio

Application September 3, 1947, Serial No. 771,967

3 Claims. (Cl. 183—51)

1

The present invention relates to filters and more particularly to filters composed of fibrous material having exterior fibers removed.

In the usual filter for suction cleaners the material has a matted napped surface to which the dirt adheres and prevents removal of the dirt when the filter is cleaned, and as a result when the filter is re-used the back pressure becomes excessive and reduces the cleaning efficiency of the suction cleaner. The present invention provides a filter fabric wherein the matted napped surface is removed to form a smooth surface upon which the dirt initially contacts, and the smooth surface functions to cause the easy removal of the dirt deposited thereon when the filter is cleaned. Removal of the matted napped surface does not injure the fibers in the body portion of the filter material and thus the filtering efficiency of the material is not reduced.

An object of the invention is to provide a filter formed from fibrous material. Another object is to provide a fibrous filter having projecting fibers shortened while retaining the necessary filtering characteristics. A further object is to provide a fibrous filter adapted for use with a suction cleaner and having the fibers in the dirt contacting surface shortened to form a smooth dirt collecting surface which can be easily cleaned. Another object is to provide a method of shortening fibers projecting from the body of a fibrous filter material. Still another object is to provide a method of treating fibrous filtering material by subjecting the material to an electrical charge to raise fibers from the body of the material and thereafter shortening the fibers by singeing the latter to substantially the body of the material. Other objects and advantages of the invention will be apparent from the following specification and drawing, wherein:

Figure 1 illustrates the filter in a suction cleaner;

Figure 2 is a view of the apparatus for creating an electrical charge in the filter material to raise the fibers and to singe the projecting fibers;

Figure 3 is a section of the filter material prior to shortening the fibers; and

Figure 4 is a section of the filter material after the fibers have been shortened on the dirt contacting surface of the filter.

The invention herein disclosed is for purposes of illustration applied to a suction cleaner comprising a casing 10 supported on runners 11 and having a suction end cap 12 and an exhaust end cap 13. The end cap 12 is provided with an inlet

2

14 for connection to an unshown hose and cleaning tool which engages a surface to be cleaned, and the rear end cap 13 has an outlet 15 which can also be provided with a cleaning tool in a manner well known in the art. A dirt filtering bag 16 is supported in the casing 10 to remove the dirt from the dirt-laden air passing through the inlet 14 into the bag, and a motor-fan unit 17 provides the suction for moving the air stream and exhausting it through the outlet 15. The filter material may be paper, cloth or other suitable material and as shown in Figure 3 prior to being processed is a single ply cloth 20 having yarns 21 secured together by warp face yarns 22, 23, and 24. The exposed surfaces 30 and 31 of the material prior to being processed is a mass of intermingled matted fibers or nap 32, and it is these fibers which retain the dirt in the usual suction cleaner bag and prevent removing all of the dirt when the bag is being cleaned.

The process for removing the matted fibers or nap 32 from the surface 30 is shown in Figure 2 and comprises a bolt of the material 20 rotatably supported on a shaft 35, and the material is wound onto a shaft 36 by moving the material in the direction of the arrow 37. The material passes through an electrostatic field formed by two electrodes 40 and 41 disposed on opposite sides of the material, and the electrodes are connected to a suitable source of high frequency current. Disposed above the electrode 40 and beneath the material 20 is a gas manifold 42 having two rows of burners 43—43 in the electrostatic field and adjacent the outer fibers of the material.

Movement of the material between the electrodes 40 and 41 causes the material to pass through the electrostatic field and the fibers receive an electrical charge and are aligned with the electric field, and as a result of such charge the nap or fibers are pulled away from and are perpendicular to the body of the material so that the fibers are no longer matted into the body of the material. While the fibers are raised from the body of the material, the burners 43—43 singe the ends of the fibers to shorten the latter and thus prevent the fibers from forming a matted surface, and the resulting surface shown at 45 in Figure 4 provides a relatively smooth dirt contacting surface from which the dirt may easily be removed when the filter is being cleaned.

The speed of movement of the material between the electrodes 40 and 41 depends upon the size of the electrodes, the strength of the electrostatic field and the heat of the singeing flame.

I have found that the voltage applied to the electrodes can be varied over a wide range and have employed voltages from 1500 to 4000 per square inch. If desired the burners 43 can be arranged to one side of the electrodes 40 and 41.

The processed filter material shown in Figure 4 is formed into the dirt filtering bag 16 with the smooth surface 45 forming the interior and the napped surface 31 the exterior of the bag. The dirt-laden air passes through the inlet 14 into the bag 16 and first contacts the smooth inner surface 45, and the remaining portion of the filter body removes the dirt from the dirt-laden air stream as the latter passes through the material, and the cleaned air is then discharged through the outlet 15.

In cleaning the bag 16, the end cap 14 and the bag 16 are removed and the dirt is easily dislodged from the bag because of the relatively smooth inner surface 45.

While I have shown and described but a single modification of my invention, it is to be understood that this modification is to be taken as illustrative only and not in a limiting sense. I do not wish to be limited to the particular structure and process shown and described, but to include all equivalent variations thereof except as limited by the scope of the claims.

I claim:

1. In a suction cleaner, a dirt filtering bag having an opening for emptying collected dirt, suction creating means for moving an air stream from the interior of said bag and through the wall thereof to remove the dirt in said air stream, said filter bag being of fibrous material including in its structure relatively long fibers projecting from the body of the material to form the exterior surface of said bag, said material including relatively short fibers projecting from the body of said material to form the inside surface of the bag, said short fibers initially contacting said air stream to remove dirt therefrom, said short fibers providing a relatively smooth surface interiorly of the bag for easily dislodging the collected dirt through said bag opening.

2. A dirt filter adapted for use in a suction cleaner having suction creating means for moving an air stream through a filter and comprising: a fibrous material including in its structure relatively long fibers and relatively short fibers projecting from opposite sides of the body of

said material, said short fibers on one side of said body being charred to present a relatively smooth surface of short fibers so disposed in the cleaner to initially contact the dirt to be removed from the air stream and collecting some of the removed dirt thereon, said relatively long fibers on the opposite side of said body being uncharred to remove any dirt remaining in the air stream, the charred short fibers forming said smooth surface initially contacting the dirt permitting easy removal of dirt collected thereon to clean said filter in comparison to any dirt which may have collected on said relatively long uncharred fibers on said opposite side of said material.

3. In a suction cleaner, a dirt filtering bag having an opening for emptying collected dirt, suction creating means for moving an air stream from the interior of said bag and through the wall thereof to remove the dirt in said air stream, said filter bag being of fibrous material including in its structure fibers shortened to substantially the body of the material to form the interior surface of said bag to initially contact the dirt, said shortened fibers so projecting from said body of the material to form an unmatted fibrous surface to provide a relatively smooth interior surface on said bag for easily dislodging the collected dirt therefrom through said bag opening.

DALE C. GERBER.
